(57) **CLAIM**

The ornamental design for the liquid infusion pump as shown and described.

DESCRIPTION

FIG. 1 is a front perspective view of the liquid infusion pump showing our new design;

FIG. 2 is a front view of the liquid infusion pump of FIG. 1; FIG. 3 is a rear view of the liquid infusion pump of FIG. 1; FIG. 4 is a side view taken from the left side of FIG. 2 of the liquid infusion pump of FIG. 1;

FIG. 5 is a side view taken from the right side of FIG. 2 of the liquid infusion pump of FIG. 1;

FIG. 6 is a top view of the liquid infusion pump of FIG. 1; FIG. 7 is a bottom view of the liquid infusion pump of FIG. 1;

FIG. 8 is a front perspective view of the liquid infusion pump showing our new design;

FIG. 9 is a first enlarged fragmentary view taken from FIG. 1; and,

FIG. 10 is a second enlarged fragmentary view taken from FIG. 1.

The broken line portions of the drawings are included to show portions of the liquid infusion pump that form no part of the claimed design.

1 Claim, 7 Drawing Sheets
